UNITED STATES PATENT OFFICE

FRANKLIN P. HAYWARD, OF EAST BRAINTREE, MASSACHUSETTS

DESIGN FOR A CHAIR

Application filed March 17, 1933. Serial No. 47,492. Term of patent 14 years.

To all whom it may concern:

Be it known that I, FRANKLIN P. HAYWARD, a citizen of the United States, residing at East Braintree, in the county of Norfolk and Commonwealth of Massachusetts, have invented a new, original, and ornamental Design for a Chair, of which the following is a specification, reference being had to the accompanying drawing, forming a part thereof.

In the drawing,—

Fig. 1 is a perspective view of a chair showing my new design;

Fig. 2 is a front elevation of the said chair;

Fig. 3 is a side elevation of the chair; Figs. 2 and 3 being drawn on a larger scale than Fig. 1.

The sides, seat and arms of the chair are of wood. The back is made of textile fabric attached to a cross piece at the upper ends of the side members and running over the seat to a point of attachment therewith beneath the front edge of the seat.

I claim:

The ornamental design for a chair substantially as shown and described.

FRANKLIN P. HAYWARD.
